(57) CLAIM

The ornamental design for a mesh screen for headache truck rack, as shown and described.

DESCRIPTION

FIG. 1 is a perspective view of a mesh screen for headache truck rack;

FIG. 2 is a front elevational view of the design;

FIG. 3 is a top plan view of the design;

FIG. 4 is a bottom plan view of the design;

FIG. 5 is a right side elevational view of the design; and,

FIG. 6 is a left side elevational view of the design.

The rear view of the design is identical to the front view and is therefore not shown.
